UNITED STATES PATENT OFFICE.

SANDFORD C. COX, OF EDISON PARK, ILLINOIS, ASSIGNOR TO COX MULTI-MAILER COMPANY, OF AUGUSTA, MAINE, A CORPORATION OF MAINE.

ADDRESSING-MACHINE.

1,104,967.

Specification of Letters Patent. Patented July 28, 1914.

Application filed July 27, 1908. Serial No. 327,979.

To all whom it may concern:

Be it known that I, SANDFORD C. Cox, a citizen of the United States, residing at Edison Park, in the county of Cook and 5 State of Illinois, have invented certain new and useful Improvements in Addressing-Machines, of which the following is a full, clear, and exact specification.

This invention relates to addressing machines for printing the address upon newspapers, pamphlets and the like, and has more especial reference to the means for feeding the slugs which bear the name or address, or other matter to be printed, into 15 the slug wheel or holder which holds and carries these slugs while the impression is being made, the invention also having reference to the means for ejecting the slugs, and to certain improvements in the slug-wheel 20 itself.

The invention has for its primary object to provide improved and simple means whereby the slug to be printed from will be positively conducted to its proper place or 25 seat in the slug wheel.

A further object of the invention is to provide improved and simple means for holding the slugs securely in place while being printed from, and to insure their 30 prompt dislodgment after the printing operation is completed.

With a view to the accomplishment of these ends, and the attainment of certain other objects which will hereinafter appear, 35 the invention consists in the features of novelty which will now be described with reference to the accompanying drawings, and more particularly pointed out in the claims.

40 In the said drawings—Figure 1 is a side elevation of the portion of an addressing machine embodying this invention. Fig. 2 is a similar view, looking at the opposite side thereof. Fig. 3 is a detail perspective view of a crank, hereinafter described. Fig. 4 is a detail perspective view of a clamp member or jaw, hereinafter described. Fig. 5 is a plan view of a portion of an addressing machine embodying this invention. 45 Fig. 6 is a detail side elevation, partly in vertical section, of the discharge end of the slug-galley or race. Fig. 7 is a front or end elevation thereof. Fig. 8 is a plan view thereof. Fig. 9 is a vertical sectional view 50 taken on the line 9, 9, Fig. 5. And Fig. 10

is a detailed perspective view of the movable jaw shaft and its operating lugs.

The slugs to be printed from, which are shown at 1 in dotted lines, are stored in a race or galley 2, of any suitable length, and in the bottom of which galley runs a tape or belt 3, which serves to urge the slugs forward against a stop 4 on an ejecting plunger 5 having an ejecting shoulder 6, which stands normally above the upper edge of the slug in such a manner as to engage the end slug and force the same downward onto a conveyer belt 7. Owing to the difference in length of various names and addresses, some of these slugs are single-line, while others are composed of a plurality of lines, and in practice the plural-line slugs are made up of a number of single-line slugs, cast separately and subsequently riveted together, the rivet being usually 75 located about mid-length of the slug—a feature which is not important with respect to this portion of the apparatus, but which will need to be taken into consideration with reference to the slug-wheel and ejecting 80 means. Ordinarily, the maximum width of slug is equal to three single-line slugs, but whatever the maximum width of slug may be, it is adapted to rest wholly upon a plurality of slug-supporting fingers 8, 9, 10, 85 three at each end of the slug contiguous to the side walls of the galley 2, as clearly shown in Figs. 7 and 8. As indicated in Fig. 8, these fingers are graduated in length, the inside fingers 10 being the longest, and 90 the difference in length between any two contiguous fingers is equal to the width of a single slug or line. Each of the fingers is provided with a tail-piece or arm 11, and to these are secured independent springs 12, 95 which hold the fingers in a horizontal position, level with the bottom of the galley or race. The stop-surface 4 of the plunger 5 being situated in a vertical plane with the extreme outer ends of the longest fingers 10, 100 it will be seen that the end slug will be pushed to a position against this stop 4, and over all of the fingers. If the slug be a single-line slug, it will rest upon the longest fingers 10 alone, and consequently when the plunger 5 descends to eject the slug it will push down merely the end slug, leaving the next slug supported upon the fingers 9. If it be a two-line slug, it will be supported upon the fingers 9, 10, alone, and consequently will 110

be likewise ejected by the plunger 5, leaving the next slug supported by the fingers 8. And if it be a three-line slug, it will be supported on all of the fingers, and will be ejected 5 by the plunger 5, the next slug remaining in place upon the fixed part 2^a of the race or galley which forms a stop for the upward movement of the fingers, whose surfaces are recessed or shouldered so as to fit 10 under the fixed bottom 2^a and at the same time have their outer ends flush with the surface of such bottom. These slug-supporting fingers and ejector, however, form no part of my present invention, as they 15 constitute the subject-matter of the claims of a Patent No. 1,033,232 issued to me July 23, 1912.

As the slug leaves the supporting fingers it falls upon the conveyer tape or belt 7, as 20 before mentioned, whose upper fold is arranged in an inclined position, and passes around pulleys 13, 14, 15, 16^a, the pulley 13 being arranged between tail-pieces or arms of the slug-supporting fingers, and the pulley 14 being journaled in suitable arms or supports 15^a and held between jaws or teeth 16 on type wheel or slug-carrier 17. These jaws or teeth 16, it will be seen, are fixed or rigid with the wheel, and are arranged in 25 pairs, with the tape or belt 7 projecting in between the teeth of each pair, so that as the wheel 17 rotates, the teeth 16 will pass upwardly at the sides of the upper fold of the belt 7 and will lift the slug 1 therefrom 30 as it rests thereon, all of the jaws 16 having their edges at one side formed on lines substantially radial to the wheel 17, so as to constitute squared firm seats for the slugs to rest on, the periphery of the wheel 17 being 35 also formed with flat or squared surfaces 18 at the inner ends of the jaws 16. After the slug finds lodgment upon the pair of fixed jaws or teeth 16, it is firmly clamped in position by a movable jaw or clamp, comprising 40 two teeth 19, 20, and a body-portion 21 having a squared passage 22, or other suitable means for receiving a squared rocker shaft 23, which is journaled in the wheel 17. The wheel is circumferentially reduced in 45 diameter between the two rows of jaws or teeth 16, so as to make room for the pivotal jaws or teeth 19, 20, and their body-portions 21, as shown in Fig. 9, and allow the teeth 19, 20, to be withdrawn wholly within 50 the arc described by the seats 18 for the slugs, and thus avoid the possibility of striking the slugs as they rest upon the belt 7 in readiness to be received on said seats. The shaft 23 is provided at one end with a crank 55 arm 24, which is rigidly secured thereto in any suitable way, and provided with a pin or crank 25 secured to one end of a spring 26, whose other end is attached to the wheel 17 in such a way that when the jaw 19, 20, 60 is open the spring will hold it open, and

when it is closed, with its teeth pressing against the teeth 16 of its companion jaw, it will hold it closed. On the end of the shaft opposite the crank 24 are secured two lugs or pins 27, 28, by means of a plate 29, 70 or other suitable agency, and these serve respectively for opening and closing the jaws. The jaws remain open until they pass the upper fold of the belt 7 when moving in an upward direction at this point, the slug 75 having then been properly lodged upon its seat 18, and in fact the closing action is preferably deferred until the fixed jaws reach a substantially upright position so that the slug will have full opportunity for 80 settling squarely upon its seat, it being immaterial how long this closing action is deferred, so long as the jaws are firmly closed before the slug reaches the impression device or stamper which presses the paper 85 against the printing surface of the slug. Any appropriate means may be employed for producing this impression, a stamper for that purpose being indicated in dotted lines at 30. When the jaws are open the lugs 90 or pins 27 are in line with a trip 31, which is in the form of a pin or rod projecting from a supporting arm 32, and so held as to be engaged by these pins or lugs 27. The arm 32 may be provided with a slot 33, 95 whereby the position of the trip 31 may be accurately adjusted in a direction radial with respect to the slug-wheel, and in order that it may be adjusted in a direction concentrically with the slug-wheel, the arm 32 100 is mounted, by means of hub 34, upon shaft 35 of the slug-wheel or otherwise arranged concentrically therewith, and it is held in place by an arm 36, having a concentric slot 38, through which passes a set-screw 39, secured to a portion 40 of the frame, or other fixed part of the machine. The lugs 28, when the jaws are closed, are in line with two opening trips 41, 42. The trip 41 is so situated as to open the jaws after the printing operation is performed, in order to permit the slug to fall into a receiving galley or chute 43, of any suitable construction, and the trip 42 is so positioned as to again 110 open the jaws before they arrive at the conveyer belt 7, in the event that they should be closed by hand, and allowed to remain in their closed position after they pass the first opening trip 41, it being sometimes the case that the attendant closes the jaw, when inspecting or repairing the machine, after it passes the first trip, and neglects to open it again. The trips 41, 42, are likewise adjustable both radially and concentrically 115 with respect to the slug-wheel, the trip 41 being held in a slot 44 in an arm 45, which carries also an arm 46 having a slot 47 in which the trip 42 is mounted, with capability of radial adjustment, and the arm 45 is formed with a concentric slot 47 through 120 125 130

which a set-screw 48 passes into frame-member 40, whereby both arms 45 and 46 may be concentrically adjusted.

Situated between the teeth 16 of the fixed jaws, and below or within the seats 18, is an ejecting band 49, which has one end attached to any suitable fixture 50, while the other end is preferably secured to an anchored spring or elastic connection 51, which serves to keep the band 49 stretched tightly around the wheel in such a way that it will lie beneath the inner edges of the slugs as they rest upon their seats 18, and will serve to strip them from their seats when they arrive at a position over the receiving galley 43, in the event they should not drop out by gravity. This band 49 is preferably of considerable width, as shown in Fig. 5, so as to avoid cutting a groove in the slugs and rendering them liable to breakage adjacent the point where the rivet is driven through the plural-line slugs, as before mentioned, and this band is situated between and straddled by the teeth 19, 20, of the movable jaws, and consequently it will be seen that these teeth impinge the slug contiguous to its ends, where it possesses the greatest strength and is securely supported at the back by the teeth 16 of the fixed jaws.

The various pulleys supporting the tapes 3 and 7 and the type wheel and plunger 5 may be connected in any suitable way for causing them to move in harmony with each other to carry out the before-described functions. As a mere example of such an operative connection, the shaft 35 of the slug wheel 17 is shown as provided with a worm-wheel 52, which is engaged by a worm 53 on a drive-shaft 54, carrying a cam 55, of suitable form, engaging a pin 56 on a crank-arm 57 carried by a rocker-shaft 58, which operates the plunger 5 in one direction, while this plunger is operated in the return direction by a spring 59, or other suitable means. The shaft 35 carries a pulley 60, connected by a belt 61 to a pulley 62 on a shaft 63, which drives the tape pulley 13, and which may be connected to shaft 64 by pulleys 65, 66, and belt 67, for driving tape pulley 68 of the tape 3.

The pulleys 15 and 16^a for supporting the belt or tape 7 may be supported by any suitable means, such as arms 69, which are suspended from the shaft 63 and connected together by bar 70, these serving to carry the pulley 15; the pulley 16^a being mounted in arms 71, pivoted at 72 to any suitable support 73, and held in place by a pin 74. To one of the arms 69 is secured a spring 75, which serves to pull the arms toward the pulley 16^a and thereby tighten the belt 7.

I claim—

1. In a machine for the purpose described, the combination of means for containing a supply of slugs, a rotary type or slug carrier

having means for holding and carrying the type or slugs while being printed from, and means fixed with relation to and movable from the supply-containing means toward said carrier for conducting the slugs into 70 said slug-holding means, said slug-holding means and said slug-conducting means projecting into overlapping planes.

2. In a machine for the purpose described, the combination of means for containing a 75 supply of slugs, a rotary type or slug carrier having means for holding and carrying the type or slugs while being printed from, and means fixed with relation to and movable from the supply-containing means toward 80 said carrier for conducting the slugs into said slug-holding means, said slug-holding means embodying spaced supports for the slugs, and said slug-conducting means projecting into the space between said supports. 85

3. In a device for the purpose described, the combination of means for containing a supply of slugs, a rotary type or slug carrier having means for holding and carrying the type or slugs while being printed from, 90 and a conveyer belt moving from the supply-containing means toward said carrier for conducting the slugs into said slug-holding means.

4. In a machine for the purpose described, the combination of means for containing a supply of slugs, a rotary type or slug carrier having means for holding and carrying the type or slugs while being printed from, and an inclined conveyer belt moving from 100 the supply-containing means toward said carrier for conducting the slugs into the slug-holding means.

5. In a machine for the purpose described, the combination of means for containing a 105 supply of slugs, a rotary type or slug carrier having means for holding and carrying the type or slugs while being printed from, and an endless conveyer belt traveling from said supply-containing means toward said carrier for conducting the slugs into 110 said slug-holding means.

6. In a machine for the purpose described, the combination of means for containing a supply of slugs, a rotary type or slug carrier having means for holding and carrying the type or slugs while being printed from, comprising spaced supports for the slugs, and a conveyer for conducting the slugs from 115 said supply-containing means to the 120 said carrier, traveling into the space between said supports.

7. In a machine for the purpose described, the combination of means for containing a supply of slugs, a rotary type or slug carrier having means for holding and carrying the type or slugs while being printed from, comprising a projecting support for the slug, and a traveling conveyer extending from the said supply-containing means to 125 130

the said carrier and projecting inwardly toward the center of the carrier beyond the plane of movement of the outer end of said support.

5 8. In a machine for the purpose described, the combination of means for containing a supply of slugs, a rotary type or slug carrier having means for holding and carrying the type or slugs while being printed from, 10 comprising two spaced supports for each slug, and an endless conveyer having one portion extending into the space between said supports and another portion arranged contiguous to said supply containing means, 15 for conducting the slugs to said supports.

9. In a machine for the purpose described, the combination of means for containing a supply of slugs, a rotary type or slug carrier having means for holding and carrying 20 the type or slugs while being printed from, embodying spaced supports for the slugs having seats for the lower or inner edges of the slugs, a stripper-band partially surrounding said rotary carrier and situated 25 inwardly with respect to said seats, in a circumferential line between said supports, and traveling means for receiving and conveying the slugs from the said supply-containing means into said seats.

30 10. In a machine for the purpose described, the combination of means for containing a supply of slugs, a rotary type or slug carrier having means for holding and carrying the type or slugs while being printed from, embodying fixed and pivoted 35 jaws, means for closing said pivoted jaws with respect to the fixed jaws as said carrier rotates, means for receiving slugs discharged from the carrier, means for opening the pivoted jaws prior to reaching said slug-receiving means, means for conducting the slugs to their position between said jaws, and means situated between said conducting means and the first said jaw-opening means, 40 for opening the jaws immediately prior to reaching the said conducting means.

45 11. In a machine for the purpose described, the combination of means for containing a supply of slugs, a rotary type or

slug carrier having means for holding and 50 carrying the type or slugs while being printed from, a conveyer belt for conducting the slugs from the said supply-containing means to the said carrier, a pulley over 55 which said belt runs, a second pulley em- braced by said belt and movable bodily in a direction concentric with respect to said first pulley, elastic means for thus bodily moving said second pulley, and a fixed idler interposed between said pulleys, and against 60 which said belt runs.

12. In a machine for the purpose described, the combination of means for containing a supply of slugs, a rotary type or 65 slug carrier having means for holding and carrying the type or slugs while being printed from, said supply-containing means embodying a plurality of pivoted supporting fingers arranged to engage the lower 70 edges of the slugs near their ends, and a movable slug-conducting means situated between said fingers and extending therefrom to said carrier, for conducting the slugs into the grasp of said slug-holding means.

13. In a machine for the purpose described, the combination of means for containing a supply of slugs, embodying pivoted slug-supporting fingers arranged at the 75 sides thereof to engage the lower edges of the slugs near their ends, a rotary type or 80 slug carrier having means for holding and carrying the type or slugs while being printed from, a traveling slug-conducting means extending from said fingers to said carrier, for conducting the slugs to said holding means, and an incline arranged between 85 said fingers and extending downwardly to said conducting means, for directing the slugs thereonto.

In testimony whereof I have signed my name to this specification, in the presence of two subscribing witnesses, on this 24th day of July A. D. 1906.

SANDFORD C. COX.
